UNITED STATES PATENT OFFICE.

STEFFEN P. NEMETH, OF CHICAGO, ILLINOIS, ASSIGNOR, BY MESNE ASSIGNMENTS, OF ONE-HALF TO BERT COATES NEMETH, OF CHICAGO, ILLINOIS.

PUTTER ATTACHMENT.

Application filed August 25, 1926, Serial No. 131,443. Renewed April 25, 1928.

This invention relates to improvements in putter attachments and its object is to provide means for automatically controlling the swing of the putter, in the game of golf, so that strokes made with this club will be uniformly accurate.

A further object is to provide such an attachment that is adjustable to suit the particular position assumed by the individual 10 player when putting.

A further object is to provide such an attachment that is cheap to manufacture, positive and efficient in operation and that can be instantly applied to the club and as readily removed when desired.

With the foregoing and other objects in view the invention consists in the combination and arrangement of parts to be herein-after fully described, particularly pointed 20 out in the claims and illustrated in the accompanying drawing which forms a part of this application and in which—

Fig. 1 is a perspective view of the putter attachment.

Fig. 2 is a plan view of a slightly modified form.

Like reference characters denote corresponding parts in both views.

Diversity of opinion is rampant, in the 30 game of golf, as to the proper method of putting. Certain instructors or authorities stating that there is more individuality in putting than in any other department of golf and that no uniform method of playing this 35 stroke is possible. Others recommend certain positions of the body, arms or legs etc. produce the best results. One result of the foregoing condition is that many of the leading players of the day, professionals and amateurs alike, are frequently weaker when playing with the putter than when engaged with any other of their clubs. It is the intention 40 of the present invention to definitely eliminate this weakness.

45 The invention comprises an angular bar 1 which is formed, as shown in Fig. 2, with the somewhat U-shaped portion having what may be termed the base 2 from which the sides 3, 4 diverge, the side 3 having the angular extension 5 and the side 4 having the angular extension 6, said extensions being identical as to shape and size and each extension 50 having an apex 7 in its structure from which its sides extend at an angle of 90 degrees to each other.

The bar 1 shown in Fig. 1 is formed at its longitudinal center with a twist 8 which disposes this portion at right angles to the adjacent portions 3, 4, all of said portions being in a straight line and the ends 5, 6 of the bar 60 being bent in a common direction at an angle of approximately 23 degrees to the main body portion thereof. Sleeve pads 9 are applied to or receive the ends of the bar 1.

To the base 2 the long arm 10, of a bracket 65 comprising also the short arm 11 connected thereto by the set screw 12, is pivotally secured by the bolt 13, while to the twisted portion 8 of the bar 1 a link 14 is secured by wing nut 15, said link 14 having a plurality 70 of perforations 16 and having the bracket 10, 11 secured thereto by the pivot bolt 13.

In operation the ends of the bar 1 are applied to the player's legs at a point above the knees, the apex 7 and the sides of each extension 5 and 6 coming against the legs; or in Fig. 1 the points at which the ends of the bar are bent take this position. The bracket 10, 11 is applied to the putter and secured by the set screw 12. The stroke is made by 80 now swinging the putter in the ordinary manner, the bracket and putter swinging from the bolt 13 as a center. In the form shown in Fig. 1 the bracket and putter will swing also from the bolt 13 as a center. The 85 link 14 is adjusted with relation to the bar 1 to correspond to the position of the player's legs, as he may stand with one leg slightly in advance of the other or with one leg straight and one bent at the knee etc.

90 What is claimed is:—

1. In a putter attachment, an angular bar, a link adjustably connected to said bar, and a bracket pivotally connected to said link.
2. In a putter attachment, a bar having its 95 longitudinal central portion twisted and its ends bent, a link adjustably connected to the twisted portion of said bar, and a bracket pivotally carried by said link.
3. In a putter attachment, a bar having its 100 longitudinal central portion twisted at right angles to the main body portion, the ends of said bar being bent in a common direction, a link adjustably connected to the twisted portion of said bar, and a bracket pivotally connected to said bracket.
4. In a putter attachment, a bar having its 105 longitudinal central portion twisted at right angles to the main body portion, the ends of said bar being bent, a perforate link ad- 110

justably connected to the twisted portion of said bar, a bracket comprising a long and a short arm portion, and a pivot bolt connecting said long arm portion and said link.

5 5. In a putter attachment, an angular bar comprising a central approximately U-shaped portion, extensions formed at the ends of said U-shaped portion, and a bracket pivotally connected to the base of the U-shaped portion
10 of said bar.

6. In a putter attachment, an angular bar comprising a central approximately U-shaped portion, extensions formed at the ends of the U-shaped portion, and a bracket pivotally connected to the base of the U-shaped portion and extending upwardly therefrom. 15

In testimony that I claim the foregoing as my own I have hereto affixed my signature.

STEFFEN P. NEMETH.
